ASH TRAY

Ernest W. Bray, Toledo, Ohio

Application August 11, 1941, Serial No. 406,380

3 Claims. (Cl. 131—241)

The invention relates to a tray which may be freely supported from any overhanging member such for instance as the top of a table or the like.

The device is not rigidly fixed to the table but is provided with a member which rests on the top of the table while the main portion of the tray itself may project from the table. Attached to the tray is a downwardly projecting member which may be curved so that its unattached end goes under the table top. Near its end the member is provided with a weight which counterbalances the tendency of the tray to tip and at the same time tends to hold more or less tightly against the top of the table the member projecting from the tray so that it is held more or less firmly but removably in position.

The projecting member which extends and rests against the table top may be attached to the tray or be made integral therewith. If desired it may consist of or have incorporated in it a wire member, the ends of which extend across the top of the tray where, alone, or associated with one or more additional cross wires they may form a rest for cigarettes or the like or means for knocking off the ash.

In the accompanying drawing Figure 1 is a transverse vertical section of one form of ash tray applied to the top of a table. Fig. 2 is a top plan view of an ash tray in position on a table. Fig. 3 is a bottom plan view of an ash tray and Fig. 4 is an enlarged fragmentary vertical section on the line 4—4 of Fig. 1.

There may be provided a hollow tray or ash receptacle 10 from one side of which projects a member 11 which may be made integral with the tray 10. It will be understood that the member 11 may be a separate piece and fastened to the tray 10 in any suitable manner. Depending from the bottom of the tray 10 is a curved member 12 which may be of any suitable form or material. The particular form illustrated may be a metal band or strip. The member 12 extends downward from the tray and is curved so that it extends substantially below the member 11 and has near its end a weighted member 13. If desired the weighted member 13 may be adjustable in any suitable manner along the member 12 so as to be placed nearer to or further from the end of the member 12.

The member 12 may be integral with the tray 10 or may be a separate member therefrom and fastened thereto in any suitable manner. As illustrated in the drawing the end of the member 12 is turned over so as to form a tongue 14. In

5 the bottom of the member 10 is formed a slot 15 which is approximately the width of the tongue 14 and a little more than twice the length of the tongue 14. At one end, for instance the end toward the left in Fig. 1, the slot 15 is open at its bottom so that the tongue 14 may be freely inserted or withdrawn therefrom. A portion of the slot 15, for instance the portion illustrated at the right in Fig. 1, may have its lower end 10 partially closed by inwardly projecting flanges 16 so that when the tongue 14 is placed in the right hand end of the slot 15 it may be locked therein and more or less firmly held in place.

15 A U-shaped wire member 17 may be placed across the top of the tray 10. The U-shaped member 17 is preferably longer than the diameter of the tray so that as shown in the drawing it extends out and becomes substantially a part of the extending member 11. When the extending member 11 is present the portion of the U-shaped member lying thereover may be omitted and when the U-shaped member extends as shown the underlying portion of member 11 may be omitted so that the extending portion of the U-shaped member 17 may form the side extending member 11. The portion of the U-shaped member 17 extending across the tray 10 may be associated with one or more additional wire-like members 18 which extend across the tray 10 to 20 form a rest for cigarette or cigar, pipe or the like. 25 The various wires may also be convenient to use for snuffing out or brushing off ashes into the tray 10.

30 In use the extension 11 or the wires 17 may be placed on the top of the projecting shelf or member 19, which may be a top of a table provided with supporting legs 20. Preferably the tray member 10 will be brought close to or in contact with the edge of the table top 19. In this 35 position the weight 13, carried by the arm 12 will extend below the table top and balance the ash tray so that the extension member 11 is braced more or less firmly and substantially flat against the top of the table 19, thus holding the tray adjusted in position indicated in Fig. 1.

40 The invention may be embodied in other forms, shapes and proportions than those illustrated and the tray may be used for any suitable purpose.

45 I claim as my invention:

50 1. In an ash tray adapted to be associated with a table or the like, a pan adapted to extend from the table, a lip extending from the pan over the table to support the pan, a member extending from the pan below the table and a

weight on the end of the member under the table to balance the tray.

2. In an ash tray adapted to be associated with a table or the like, a pan adapted to extend from the table, rods extending across the pan and forming a lip extending from the pan over the table to support the pan, a detachable member extending from the pan below the table and a weight on the end of the member under the table to balance the tray.

3. In an ash tray adapted to be associated with a table or the like, a pan adapted to extend from the table, a lip extending from the pan over the table to support the pan, rods extending across the pan, a detachable member extending from the pan below the table, and a weight on the end of the member under the table to balance the tray.

ERNEST W. BRAY.
